UNITED STATES PATENT OFFICE

WAYNE Z. FRIEND, OF CHARLESTON, WEST VIRGINIA, ASSIGNOR TO BALTIMORE GAS ENGINEERING CORPORATION, A CORPORATION OF MARYLAND

FRACTIONATION APPARATUS

Application filed September 17, 1928. Serial No. 306,564.

This invention relates to improvements in apparatus used in the fractionation of liquids, and especially to an apparatus for the fractionation of liquids composed of soluble fractions having relatively close boiling points, such as the hydrocarbon fractions of natural gasoline.

One of the objects of the invention is to provide a rectifying column, the internal portions of which are accessible for repairs, cleaning or adjustment.

Another object is to furnish a fractionating column of the bubble cap type; in which the caps are less complicated, cheaper to manufacture, and fewer in number than in the columns heretofore proposed, and also in which said caps are accessible for replacement if corrosion should take place.

A still further object is to furnish a rectifying column in which more thorough equilibrium may be obtained on each plate, owing to the fact that the liquid is circulated as well as agitated.

Another object is to provide a fractionating column of the bubble cap type, in which the caps are elongated; the caps on adjacent plates being arranged at angles to each other to assist in changing the direction of the gas and liquid flow, and to keep the streams more thoroughly mixed.

A still further object is to furnish a bubble cap fractionating column in which the available outlet vapor area of each plate is greater than that of the conventional round caps, which permits a more compact apparatus and increases the capacity of the column.

A further object is to produce a rectifying column wherein the pressure drop through the column is decreased, thus reducing to a minimum the loss of pressure resulting from the use of a plate and cap column.

Other objects will appear as this description proceeds.

I shall describe this apparatus as it is applied to the fractionation of natural gasoline, although I do not wish to limit the use of my invention to this particular duty, since I am aware that the invention is applicable to the fractionation of a wide variety of liquids.

The nature and advantages of my invention

will better be understood when the following detail description is read in connection with the accompanying drawing; my invention residing in the construction, combination and arrangement of parts as claimed.

Referring to the drawing,

Fig. 1 is an elevation, partly in vertical section of my improved fractionating tower.

Fig. 2 is a horizontal sectional view of the same, taken on line 2—2 of Fig. 1.

Fig. 3 is an enlarged vertical sectional view of a detail of one of the plates.

In the drawing, 1 designates the shell of my improved column which is of conventional construction, having a closed top plate 2, and a bottom 3, provided with a manhole, closed by a removable cover 4.

As is usual in plate type columns, the tower in the present instance, is provided with a multiplicity of horizontally disposed plates 5 of the same diameter as the inner diameter of the shell, and secured to said shell in properly spaced relation, by any suitable means, (not shown).

Each plate, as best shown in Fig. 2, has a centrally disposed aperture closed by a removable plate (c'), which may be removed from the lower side of the plate. Obviously, after the manhole plate 4 is removed, the operator may remove the various covers (c') and thus gain access to the interior of the column for making repairs, cleaning or adjustment.

Diametrically opposite overflow pipes (a), depend from each plate, and their lower ends terminate within a short distance of the next lower plate, and also within annular flanges or rings (b) mounted on the upper surface of the next lower plate. It will be noted from Fig. 2 that the flanges (b) of a plate are diametrically oppositely disposed, and located at 90° relatively to the overflow pipes (a) of that plate, and as each plate is arranged at 90° relatively to the next adjacent plate, it will be seen that the lower ends of the overflow pipes will come within the rings (b) of the plates just below.

The liquid overflowing through pipes (a), enters the cups formed by the flanges (b) and is then caused to take tortuous path

ways, as shown by the arrows in Fig. 2, toward the overflow pipes (a) of that particular plate. The baffles for effecting this, are formed by the special vapor outlets and the caps which I have devised for the same. In this particular instance, each plate is provided with a number of preferably parallel vapor outlet openings (d), each formed by an elongated endless flange which projects upwardly from the plate. It will be noted that some of these flanges are singular and project substantially all the way across the plate, but terminate a short distance from the edge of the plate, while alternate flanges are doubled or arranged end to end, and the outer ends of each of these double or pair of flanges extends to the edge of the plate. Consequently, the upper surface of the plate is obstructed or baffled by a multiplicity of flanges so arranged that the liquid must travel in tortuous paths.

Each of the flanges (d) cooperates with an elongated cap (d'), which, as best shown in Fig. 3, has its lower edges notched and resting on the upper surface of the plate. Due to this construction, the vapors or gases rising through the flanges (d) are caused by the caps (d') to turn downwardly and exit into the layer of liquid which is flowing over the plate toward the overflow pipes of that plate.

As before stated, adjacent plates are arranged at 90° relatively to each other, and consequently, the flanges (d) and caps (d') of each plate are arranged at 90° relatively to the next adjacent plate or plates.

The apparatus herein described has the following advantages over the conventional type of fractionating column.

1. It is accessible for repairs, cleaning or adjustment.

2. The caps are less complicated, cheaper to manufacture, fewer in number and accessible for replacement if corrosion should take place.

3. More thorough equilibrium is obtained on each plate because the liquid is circulated as well as agitated.

4. The rotation of each plate 90° with reference to the vertical axis of the column assists in changing the direction of the gas flow and keeps it more thoroughly mixed.

5. The available outlet vapor area is greater than that of the conventional round caps which permits a more compact apparatus and increases the capacity of the column.

6. The pressure drop through the column is decreased, thus reducing to a minimum the loss of pressure resulting from the use of a plate and cap column.

From the foregoing it is believed that the construction, operation and advantages of the invention may be readily understood, and I am aware that various changes may be made in the details disclosed without departing

from the spirit of the invention, as expressed in the claims.

What I claim and desire to secure by Letters Patent is:

1. In a fractionating apparatus, a series of superposed plates, a shell enclosing said plates, a manhole in each plate, a removable cover completely closing each manhole, and a manhole in the shell provided with a removable cover to permit the operator to gain access to the interior of the shell and plates.

2. In a fractionation apparatus, a closed shell, superposed plates horizontally positioned in spaced relation within the shell, the plates and one end of the shell being provided with registering manholes, and removable covers completely closing said manholes.

In testimony whereof I affix my signature.

WAYNE Z. FRIEND.
